UNITED STATES PATENT OFFICE.

THOMAS L. VAUGHN, JR., OF DUNN, NORTH CAROLINA.

IRONING BOARD AND SUPPORT THEREFOR.

Application filed May 18, 1922. Serial No. 561,968.

To all whom it may concern:

Be it known that I, THOMAS L. VAUGHN, Jr., a citizen of the United States, residing at Dunn, in the county of Harnett and State 5 of North Carolina, have invented certain new and useful Improvements in Ironing Boards and Supports Therefor, of which the following is a specification.

My invention relates generally to a combination ironing board and a support therefor, one of the objects of the invention being the provision of an ironing board, and a support therefor, so designed and constructed that the board may be quickly and 10 easily applied to its support, and rigidly secured in its operative position, and as easily detached therefrom.

Another object of the invention is the provision of a board and support so constructed that, when in use, the ironing pressure upon the board will operate to more firmly hold the support against movement 20 longitudinally of the board.

Another object is to provide means 25 whereby the board, when in inoperative position, may be held within the support, including means for retaining the support in its folded condition, and other means to prevent separation of the board from the support.

The above and other objects of the invention will be more particularly pointed out in the specification, in referring to the drawings forming a part thereof, in which

Figure 1 is a perspective view of the board and its support, in operative position;

Fig. 2 is a partial sectional, side view, showing the support and board in inoperative position in full lines, and in operative position in dotted lines;

Fig. 3 is an enlarged detail of the bottom of an end of the board;

Fig. 4 is a modification showing a somewhat different method of attachment of the board to the support, and

Fig. 5 is a detailed sectional view showing one of the detents for frictionally holding the board in its inoperative position.

In the drawings the support is generally indicated by the letter A and the board by the letter B. As here shown the support A comprises two upright side members 1, connected at the bottom, by screws or otherwise, to a foot member 2. The front faces of the uprights 1 are connected by a brace 3,

while the rear faces of the uprights 1 are connected by two or more braces 4, 4, located above the plane of the brace 3. The braces 3 and 4 may be rigidly secured in 60 any manner to the uprights 1.

In the construction shown in Figs. 1 and 2, the front face of each upright 1 is provided with pegs or projections 5, located in planes between the brace 3 and the lower 65 brace 4, and between the two adjacent braces 4. These projections 5 may be made of any material, or may be formed integral with the upright 1.

Pivoted to the brace 3, by a 70 hinge 6, and extending in front thereof and downwardly therefrom, is a strut member C. A base member 7, provided with a foot 8 is pivotally connected at its rear end to the foot member 2 of the upright A, by 75 means of a hinge 9.

As shown in the drawings, the strut C is composed of upper and lower sections, 10 and 11, connected by a hinge 12. Both ends of the section 10 are cut at right angles to the plane of the body, as is also the top end of the section 11. The lower end of the section 11 is beveled off to cause it to lie parallel to the top surface of the base member 7, and between said beveled end and said surface, is secured a hinge 13, which secures the section 11 to the member 7, in such a manner that, in the position shown in Fig. 1, the two plates 14 and 15 of the hinge 13 are in contact, and form a metal to metal 80 contact to receive any pressure upon the board.

Pivoted at 16, to the bottom and towards the rear end of the board B, is a bar 17, as shown in Fig. 3. The swing of said bar is 95 limited by stop members 18 and 19 as shown, and the bar is adapted to swing into a position to extend longitudinally of the board, as shown in dotted lines, or to a position transverse to said board, with its ends 100 extending beyond the edges thereof, as shown in full lines in Fig. 3.

When it is desired to place the board B in operative position, the bar 17 is swung until its side engages the stop member 18, as 105 shown in Fig. 3. In this position the ends 17' extend beyond the edges of the board B. The end of the board is then inserted under the lower face of one of the braces 4, depending upon the desired height of the 110 board, and the ends 17' of the bar 17, will rest upon the projections 5. The projec-

tions 5 are so arranged, with relation to the braces 4 thereabove, that the distance between the upper surface of the projection and the lower surface of the brace, is practically equal to the combined thickness of the board B and the bar 17, as shown in dotted lines, Fig. 2. Furthermore, since the width of the rear end of the board B is such as to provide only scant clearance in its passage between the uprights 1-1, the board B, and bar 17, closely fit in the seat provided by the uprights 1-1, the projections 5-5, and the lower surface of the brace 4.

15 The pressure of the ironing operations cannot dislodge the board, because of the binding action applied thereto between the projections 5 and the brace 4; it cannot shift laterally, because its edges would contact 20 the uprights 1. Consequently the board is firmly and securely held in the position shown in Fig. 1.

On account of the novel construction of the strut C, and its novel connection to the 25 brace 3 and base 7, the ironing operations do not cause the support to vibrate or "wobble". With the device set up as shown in Fig. 1, pressure upon the end of the board B would naturally tend to rock the support 30 A to the right. But such movement applies pressure to the squared joint at the meeting ends of the sections 10 and 11, and, since these ends are squared, and the sections, at this time, are virtually continuous, the pressure 35 is transmitted directly to the lower end of the section 11, and applied to the hinge 13. The hinge plates 14 and 15 are in flush contact, and take up this pressure throughout their entire surface, and it is applied 40 to the base 7 and to the foot 8. By this construction the center of gravity is always far enough to the right to prevent tilting of the support, and a solid and non-vibrating structure is possible.

45 In disassembling the device, the board B is merely pulled out from between the uprights. The bar 17 is then turned until it is in the position shown in dotted lines Fig. 3, its end engaging the stop 19, and the rear 50 end of the board is then passed downwardly between the uprights 1-1, and between the braces 3 and 4, as shown in Fig. 2.

In order to bind the board in its inoperative position, I provide a cam member 20 55 upon the inside lateral face of each of the uprights 1. As shown in Figs. 1, 2 and 5, said cam 20 is pivotally mounted upon said upright, the pivot pin 21 passing through the cam at a point nearer its straight or 60 rear edge. The front edge of the cam is beveled at the top, and the front face, opposite the pivot 21, is so spaced from the adjacent foot piece 2, of the upright, that the end of the board is squeezed tightly be- 65 tween said cam and said piece 2. Normally

the cam 20 is in the position shown in dotted lines in Fig. 5. When the board is inserted to inoperative position, the lower end thereof strikes the cammed surface of the member 20, rides downwardly upon said cam, and pushes the lower end of the board forwardly against the foot piece 2, and forces the rear end of the member 20, rearwardly, thereby binding or gripping the lower end of the board. At the same time, and on account of the proportions of the board, and the location of the upper brace 4, the brace 3, and the location and construction of the bar 17, the board is bent slightly out of its normal longitudinal line, and held under tension in its position. This tension is caused by the engagement of the upper end of the board with the brace 4, the engagement of the lower end of the board with the member 20, and the engagement of the bar 17 with the brace 3, at a point which causes the board to slightly bend rearwardly opposite the brace 3, not shown in the drawings.

When the board is raised from its inoperative position the tendency of the lower end of the board to spring rearwardly, pushes the top of the member 20 to the left, to the position shown in dotted lines in Fig. 5.

In order to retain the base 7 in position, when the support is collapsed, a hook 22 is pivotally mounted upon the brace 3, and adapted to engage a pin 23, extending from the edge of the base 7, as shown in Figs. 1 and 2.

The board B is preferably formed of material having some inherent resiliency. This resiliency causes a slight yield to the board, under the ironing pressure, whereby the customary padding may be eliminated, although this padding may be provided where desired. The resiliency of the board also permits of flexure when it is inserted into its inoperative position, as hereinbefore described, thereby facilitating the insertion thereof into its tight seat, as shown in Fig. 2, and rendering the latter part of this operation automatic, in so far as the wedging feature is concerned.

A modification is shown in Fig. 4 where- 110 in the projections 5 are dispensed with, and the bar 17 is fitted into slots formed in the front face of the uprights 1-1.

Fig. 4 also shows extensions 1^a on the lower front faces of the uprights 1, at the bottom thereof. This construction permits a shift of the center of gravity when the board and support are in the collapsed position shown in Fig. 2, whereby the structure will stand alone. In lieu of the exten- 120 sion 1^a, a hook 24 may be fastened to the top of the brace 4, for engagement with a staple or other device, fixed to a rigid support.

Various modifications of my invention 130

may be suggested to those skilled in the art, but I consider my invention broad enough to cover all embodiments which fall within the scope of the appended claims.

5 I claim:

1. In combination, with an ironing board, a support therefor provided with uprights carrying transversely extending braces adapted to limit lateral movement of the 10 board when placed in inoperative position between and longitudinally of said uprights and cam elements pivotally carried by the lower portion of said uprights and adapted to clamp the board when the latter is moved 15 into inoperative position and to press against the lower portion of said board,

whereby the board is held under tension, substantially as described.

2. In combination, with an ironing board, a support therefor provided with uprights 20 adapted to receive the board therebetween of means carried by said uprights whereby downward pressure upon the board will cause a gripping action to be automatically applied to the lower end thereof said means comprising beveled members pivotally carried by the uprights, substantially as described. 25

In testimony whereof I affix my signature.

THOMAS L. VAUGHN, JR.
